UNITED STATES PATENT OFFICE.

SAMUEL CHRISTOPHER McKEOWN, OF NEWARK, NEW JERSEY, ASSIGNOR TO SPLITDORF ELECTRICAL COMPANY, OF NEWARK, NEW JERSEY, A CORPORATION OF NEW JERSEY.

IGNITION MECHANISM FOR INTERNAL-COMBUSTION ENGINES.

1,262,534.

Specification of Letters Patent.

Patented Apr. 9, 1918.

Application filed June 21, 1916. Serial No. 104,937.

To all whom it may concern:

Be it known that I, SAMUEL C. McKEOWN, a citizen of the United States, residing at Newark, in the county of Essex and State of New Jersey, have invented certain new and useful Improvements in Ignition Mechanism for Internal-Combustion Engines, of which the following is a specification, reference being had to the accompanying drawing.

My invention relates to means for supplying the initial sparks to internal combustion engines, and is particularly designed for use in connection with such engines when applied to motor vehicles, aeroplanes, or the like.

In large multi-cylinder engines it is quite difficult to crank by hand, and for obvious reasons, on many aeroplane engines, mechanical starting devices are not employed. Such engines are now provided with eight or more cylinders, and the magneto is so geared to these engines that when the engine is turned over by hand the magneto 25 rotor is moved so slowly that the spark generated is quite inadequate to ignite the cylinder charge.

To eliminate the above conditions it is necessary to either use a battery in connection with the magneto for starting, which is objectionable—especially on aeroplanes—by adding complication and weight, or a separate hand-operated magneto is used in addition to the service magneto—also 35 obviously objectionable, or the service magneto is provided with a so called "impulse starting" device adapted to quickly move the rotor part of a revolution—which is objectionable in that only a single spark is 40 generated, which may not ignite the charge in the engine and which cannot be repeated without re-setting the device.

My invention eliminates all of the foregoing objections and includes in one 45 mechanism all of the features necessary to both start and run the engine.

The arrangement is simple and of few parts, and the magneto proper of known design and efficiency.

For the sake of illustration I will show my 50 invention as applied to the type of magneto known in trade as the "Dixie," although it is obvious that there are other types that

may be utilized as well. While I show one embodiment of the invention, it will be understood that I do not desire to limit myself to the precise arrangement herein described.

In the accompanying drawings in which like figures of reference denote the same parts wherever they are shown, Figure 1 is a view partly in section of a magneto embodying my invention; Fig. 2, a view partly in section at right angles to the view Fig. 1 and showing the auxiliary breaker mechanism; Fig. 3, a view of the rotor clutch member; Fig. 4, a view of the shaft clutch member; and Fig. 5, a diagram of the circuits of the device.

The magneto here shown for the sake of illustration comprises the permanent magnets 1 and the supporting base or frame 2, in which is embedded the pole pieces 3 and 4 supporting the core carrying the generating windings or coil 5. In this field structure is supported in any suitable manner—such as by the end plates 6 and 7—a rotor consisting of the shaft 8 having rigidly connected thereto the driving gear 9 adapted to mesh with a gear (not shown) 30 on a movable part of the engine. It is obvious that the shaft 8 may be driven in any other way, as long as it is positively driven in synchronism with the engine.

Carried upon the shaft 8 and revoluble 35 thereon are the magnetic members 10 and 11 constituting the revolving polar extremities of the magnets 1. These members are connected together to form a unitary rotor by means of the hollow block 12.

Carried on the shaft 8 is the clutch member 13 having a slot or keyway 14 for the shaft key 15. This clutch member has a toothed face, as shown at 16, normally held in engagement with the toothed face 17 of 95 the rotor member 10 by means of a suitable spring 18, it being understood that 13 has enough lateral play to permit its engagement and disengagement with 10 as herein-after described.

Mounted upon the laterally extending hollow shaft 19 of the rotor member 10 is the gear 20 adapted to be engaged by the gear 21, and it will be seen that when 20 is rotated in the direction of arrow 22 the 105 unit rotor comprising the parts 10, 11 and

12 may revolve upon the shaft 8, the clutch faces 16 and 17 sliding out of engagement against the pressure of spring 18.

It will also be obvious that, upon the 5 rotation of gear 9 in the direction of arrow 23, the teeth in the faces 16 and 17 engage, and that thereupon the entire rotor structure will be locked to and turn with the shaft 8. The number of teeth in 16 and 17 10 are such as to always properly position the unit rotor on shaft 8 in proper time with the engine.

I shall now describe how this invention will start an engine either at rest, or that 15 is being turned very slowly, as is sometimes done with aeroplane engines when starting. 24 denotes a suitable shaft, such as the starting crank of the engine, having thereon a handle 25 and a suitable sprocket or gear 26. 20 27 denotes an auxiliary shaft driven from said shaft 24, although it is obvious that handle 25 may be connected directly to end 28 of shaft 27. Loosely mounted upon shaft 27 is the sleeve 29 to which is rigidly attached the gear 21. The sleeve 29 is provided with a diagonal slot 30 in which is positioned the pin 31 rigidly secured to shaft 27. When shaft 27 is rotated in the direction indicated by the arrow 32 pin 31 25 will occupy the position shown at Fig. 1, and gear 21 will be rotated in the direction shown by arrow 33. This forces the sleeve 29 outwardly so that the gears 20 and 21 are in mesh as shown in Fig. 1 and are 30 revolved, causing a rotation of the unit rotor structure 10, 11, and 12, as previously described.

Suitable provision must be made for interrupting the primary current in the magneto in unison with the manual operation of the rotor, so I provide the auxiliary interrupter mechanism consisting of the insulated contact 34 and movable contact 35, the latter having a projecting bumper 36 adapt- 40 45 eq to be engaged by the cam 37 shown at dotted lines in Fig. 2, and positioned on and really forming a part of the unit rotor structure. This auxiliary interrupter mechanism operates in synchronism with the rotation 50 of the rotor independent of shaft 8, thereby properly timing the magneto current in a well known manner.

The spark timing in relation to the engine is accomplished in any well known manner, 55 such as the rocking of the entire field structure comprising the pole pieces 3 and 4, the coil 5, and the auxiliary interrupter members 34 and 35, which, with the type of magneto shown, maintains the spark always 60 at its maximum either advanced or retarded.

It will be obvious, for the spark to be effective at the engine, that the magneto distributor 38—which may be of any suitable type—must be in connection with some one 65 of the spark plug cables indicated at 39.

This is accomplished by driving the distributor mechanism by the gear 40 carried upon the shaft 8, which is always in synchronism with the engine; therefore, practically at all times the distributor is in the proper 70 position to deliver current to some one of the spark plug cables, and during the independent rotation of the rotor, sparks will be delivered to the particular plug to which the distributor connects. A rain of sparks 75 will be delivered to said plug as long as the handle 25 is turned, so that the advantage of being able to deliver more than a single spark is attained.

It will be evident that a false spark can- 80 not be made in the cylinders of the engine, as the operation of the auxiliary interrupter is dependent upon the position of the contacts of the service interrupter hereinafter described. If said service interrupter is not 85 open, then the engine may be turned slightly until it is, this service interrupter being operated by shaft 8. This also insures the distributor being in contact with some one of the spark plugs. 90

I will now describe the normal or running operation of the magneto.

The gears 20 and 21 being in mesh and being revolved by hand, as just described, a rain of sparks will be delivered to some 95 one of the cylinders. Upon the engine starting, gear 9 is thereby revolved in the direction of the arrow 23, whereupon the teeth in clutch faces 16 and 17 engage, and the rotor is revolved in the same direction 100 as when driven by hand. This immediately increases the speed of gears 20 and 21, and shaft 27 accordingly lags in a reverse direction from arrow 33, whereupon pin 31 travels up the slot 30, and sleeve 29 is there- 105 by moved to the right, Fig. 1, and gears 20 and 21 are disengaged. A friction brake 41 is provided to hold sleeve 29 in this position.

As gear 33 comes out of mesh it engages the end 42 of the plunger 43, which is normally pressed outwardly by spring 44. The end 43 of said plunger rides under and engages the movable contact member 35 of the auxiliary interrupter and disables the same. The service interrupter inclosed in the usual 115 casing 45 and driven by the cam 46 rigidly secured to shaft 8 now operates in the usual manner.

The circuits of the service and auxiliary interrupters, together with other elements 120 of the device are clearly shown in Fig. 5, the service interrupter being indicated by the numeral 47, and the auxiliary interrupter by the numeral 48. It will be remembered that the auxiliary interrupter 48 is only operated during the manual rotation of the rotor of the magneto when starting, and is then immediately disabled, the service interrupter 47 being the one employed during the normal running of the engine. It will 125 130

also be remembered that the operation of the auxiliary interrupter 48 is dependent upon the position of the service interrupter 47, for timing reasons.

5 Having thus described my invention, I claim:

1. In combination with an internal combustion engine, ignition instrumentalities including a magneto having a rotatable shaft 10 and a flux shifting member mounted on said shaft, a clutch adapted to operatively connect said shaft and said flux shifting member, means whereby said shaft may be driven from a moving part of the engine, and means 15 for disengaging said clutch whereby the flux shifting member may be rotated independently of the shaft.

2. In combination with an internal combustion engine, ignition instrumentalities including a magneto having a rotatable shaft 20 and a flux shifting member mounted on said shaft, a clutch adapted to operatively connect said shaft and said flux shifting member, means whereby said shaft may be driven 25 from a moving part of the engine, and means for rotating said flux shifting member independently of said shaft, said clutch being constructed so as to permit the flux shifting member to be rotated in the direction 30 of the normal rotation of the flux shifting member by the shaft when said shaft is at rest.

3. In combination with an internal combustion engine, ignition instrumentalities including a magneto having a rotor, a shaft 35 therefor, on which said rotor is mounted, means for connecting the shaft to the rotor when turned in a direction for normal rotation of said rotor, said means permitting 40 the rotor to be rotated in said normal direction when the shaft is at rest, means whereby the shaft may be driven through a moving part of the engine and hand operated means for rotating the rotor when the 45 shaft is at rest, said hand operated means including devices automatically brought into engagement with each other upon the turning of the hand operated means to rotate the rotor and automatically disengaged from 50 each other when the rotor is operated by the shaft.

4. In combination with an internal combustion engine, ignition instrumentalities including a magneto having a rotor, a shaft 55 therefor, on which said rotor is mounted, means for connecting the shaft to the rotor when turned in a direction for normal rotation of said rotor, said means permitting 60 the rotor to be rotated in said normal direction when the shaft is at rest, means whereby the shaft may be driven through a moving part of the engine and hand operated means for rotating the rotor when the shaft is at rest, said hand operated means including 65 gears adapted to intermesh when said

hand operated means is rotated in a direction for rotating the rotor and whereby said gears are caused to be disengaged from each other when the rotor is operated by said shaft.

70

5. In combination with an internal combustion engine, ignition instrumentalities including a magneto having rotatable members adapted to be driven from a moving part of the engine, a clutch adapted to operatively connect said rotatable members when one of said members is rotated by the engine and means for rotating the other member, said means including an operative shaft having a sliding gear connection with 80 a gear on said last named member.

75

6. In an ignition dynamo, a driving shaft adapted to be positively driven, a rotor mounted on said shaft and revoluble thereon, a clutch adapted to normally drive said rotor from said shaft, interrupter mechanism operated from said shaft, auxiliary interrupter mechanism operated from said rotor, and means for disengaging from and revolving said rotor on said shaft independently thereof, substantially as described.

85

7. In an ignition dynamo, a shaft adapted to be positively driven, a rotor mounted thereon, means for driving said rotor from said shaft, means for disengaging said rotor from 95 said shaft and driving the said rotor independently thereof, interrupter mechanism operated by the rotation of said shaft, and auxiliary mechanism operated in synchronism with the independent rotation of said 100 rotor, substantially as described.

90

8. In an ignition dynamo, a rotating shaft, a generating element supported thereon and adapted for normal rotation therewith, means for rotating said element independently of said shaft, said means including an auxiliary shaft supported by the framework of said dynamo, interrupter mechanism adapted to be operated by said first mentioned shaft, and auxiliary interrupter 110 mechanism adapted to be operated synchronously with the independent operation of said generating element, substantially as described.

105

9. In an ignition dynamo, an operating shaft, a rotor carried on said shaft and independently revoluble thereon, interrupter mechanism adapted to be operated by said shaft, interrupter mechanism adapted to be operated by said rotor, and means for disabling said last mentioned interrupter.

115

10. In an ignition dynamo, an operating shaft, a rotor carried on said shaft and independently revoluble thereon, interrupter mechanism adapted to be operated by said shaft, interrupter mechanism adapted to be operated by said rotor, means for revolving said rotor on said shaft, and means operated by said last mentioned means for disabling said last mentioned interrupter.

120

125

130

11. In an ignition dynamo, a coil-carrying field structure, an operating shaft, a rotor carried on said shaft independently revoluble thereon and positioned within said field structure, interrupter mechanism adapted to be operated by said shaft and secured to said field structure, and interrupter mechanism adapted to be operated by said rotor carried on said field structure. 55
12. In an ignition dynamo, a permanent magnet, a coil-carrying field structure having poles positioned at right angles of said magnet poles, a shaft passing through said magnet, a rotor carried on said shaft independently revoluble thereon and embraced by the poles of said field structure, interrupter mechanism operated by said shaft and carried on said field structure, interrupter mechanism independent of said first mentioned mechanism, means for rotating said rotor, and means adapted to be operated in synchronism with said last means for disabling said last interrupter. 60
13. In combination with an internal combustion engine, an ignition dynamo having a shaft positively driven by the engine and including a rotor carried by said shaft and independently revoluble thereon, interrupter mechanism actuated in synchronism with the normal running of said shaft, means for revolving said rotor independent of said shaft, and interrupter mechanism actuated in synchronism with the independent operation of said rotor, substantially as described. 70
14. In combination with an internal combustion engine, an ignition dynamo having a shaft positively driven by the engine and including a rotor carried by said shaft and independently revoluble thereon, interrupter mechanism actuated in synchronism with the normal running of said shaft, means for revolving said rotor while the engine is at rest, and interrupter mechanism synchronously operated during the last mentioned actuation of said rotor. 75
15. In combination with an internal combustion engine, an ignition dynamo having a shaft positively driven by the engine and including a rotor carried by said shaft and independently revoluble thereon, interrupter mechanism actuated in synchronism with the normal running of said shaft, means for
- for revolving said rotor while the engine is at rest, interrupter mechanism synchronously operated during the last mentioned actuation of said rotor, and means for disabling said last interrupter when said engine-driven shaft is operating, substantially as described. 80
16. In combination with an internal combustion engine, an ignition dynamo having a shaft positively driven by the engine, a rotor carried by said shaft and independently revoluble thereon, interrupter mechanism actuated in synchronism with the running of said shaft, and auxiliary interrupter mechanism operatively controlled by the position of said first interrupter mechanism for the purpose specified, substantially as described. 85
17. In combination with an internal combustion engine, an ignition dynamo having a distributor, a shaft positively driven by the engine and driving said distributor, a rotor carried by said shaft and independently revoluble thereon, interrupter mechanism actuated in synchronism with the normal running of said shaft, means for revolving said rotor from said shaft, means for revolving said rotor independently of said shaft, and interrupter mechanism actuated in synchronism with the independent operation of said rotor. 90
18. In combination with an internal combustion engine, an ignition dynamo having a distributor, a shaft positively driven by the engine and driving said distributor, a rotor carried by said shaft and independently revoluble thereon, interrupter mechanism actuated in synchronism with the normal running of said shaft, means for revolving said rotor from said shaft, means for revolving said rotor independently of said shaft, interrupter mechanism actuated in synchronism with the independent operation of said rotor, and means operated by the running of said engine for disabling said last interrupter. 95
